UNITED STATES PATENT OFFICE.

MATTHEW J. BOGERT, OF DEMAREST, NEW JERSEY.

DESIGN FOR A DRUG-BOX.

SPECIFICATION forming part of Design No. 23,415, dated July 3, 1894.

Application filed April 3, 1894. Serial No. 506,223. Term of patent 7 years.

To all whom it may concern:

Be it known that I, MATTHEW J. BOGERT, a citizen of the United States, residing at Demarest, in the county of Bergen and State of New Jersey, have invented a new and original Design for Drug-Boxes, of which the following is a specification.

The invention relates to a new and original design for drug boxes.

- o The object of the present invention is to provide an ornamental and attractive drug box; and the essential feature resides in a drug box having a cover provided near its upper edge with a circumferential corrugation, and having a lower smooth or plain portion of much greater width than the corrugation, and a body portion having upper and lower narrow circumferential corrugations and a broad plain intervening circumferential panel portion.

In the drawings—Figure 1 is a perspective view of a drug box showing my new and original design. Fig. 2 is an elevation, the cover being separated from the body of the box.

- 25 Referring to the drawings, 1 designates a cylindrical drug box having a flat top 2 and bottom 3, and provided on the cover 4 at the upper edge thereof with a narrow circumferential corrugation 5, and having below the
- 30 narrow corrugation 5 a much broader plain circumferential portion 6.

The body of the box is provided with narrow upper and lower circumferential corrugations 7 and 8, and a broad intervening smooth panel portion 9, occupying the entire 35 space between the upper and lower corrugations 7 and 8.

It will be apparent that the drug box with its ornamental arrangement of narrow corrugations and broad panels presents an attractive 40 appearance.

What I claim is—

The design for a drug box herein shown and described, the same comprising a cylindrical body portion having a flat bottom and cylindrical sides having narrow upper and lower circumferential corrugations and a broad intervening smooth panel portion occupying the entire space between the said corrugations, and a cylindrical cover having a flat 50 top and provided at its upper edge with a narrow circumferential corrugation and having a much broader plain circumferential lower portion 6, as set forth.

In testimony that I claim the foregoing as 55 my own I have hereto affixed my signature in the presence of two witnesses.

MATTHEW J. BOGERT.
